UNITED STATES PATENT OFFICE.

WALTER P. CHISHOLM, OF SHERMAN, TEXAS, ASSIGNOR OF ONE-HALF
TO J. A. LADD, OF SHERMAN, TEXAS.

WIRE-STRETCHER.

No. 838,079.

Specification of Letters Patent.

Patented Dec. 11, 1906.

Application filed December 4, 1905. Serial No. 290,246.

To all whom it may concern:

Be it known that I, WALTER P. CHISHOLM, a citizen of the United States, residing at Sherman, in the county of Greyson, State of Texas, have invented certain new and useful Improvements in Wire-Stretchers; and I do hereby declare the following to be a full, clear, and exact description of the invention, such as will enable others skilled in the art to 10 which it appertains to make and use the same.

This invention has relation to stretching wire for any purpose—as, for instance, to get it in the best condition for fastening it to 15 posts or poles in building fences or for splicing it or for any other reason.

It is the object of the invention to provide a wire-stretcher which will be at once convenient and ready for use in all respects for 20 which it is intended and be simple and strong, making it durable and handy.

The invention consists of parts and a combination of parts which when associated and combined, as hereinafter set forth, and 25 pointed out with particularity in the subjoined claims will constitute a new and improved contrivance for the purposes specified.

Reference is to be had to the annexed 30 drawings, and to the letters of reference marked on the same, forming a part of this specification.

In the drawings, Figure 1 is a plan view of the complete machine. Fig. 2 is a side elevation. Fig. 3 is a separate view of the wire-holding device and its jaws. Fig. 4 is a vertical longitudinal section on line 4 4 of Fig. 1. Fig. 5 is a section on line 5 5 of Fig. 1.

The same letters of reference show the 40 same parts or features, as the case may be, wherever they occur.

In the drawings, *a* designates the main frame of the machine, which is made of suitable material and strength, as well as shape. 45 On opposite sides of the contracted portion *b* of the rear end of the frame on one side is a staple or eyed bolt *c*, to which one end of the chain *d* to be passed about a post *e* or similar means is fastened, the said chain being for 50 the purpose of adjustment to a hook *f* at the other side. Suitable means, as a pivot-bolt *g*, is provided between the sides of the frame,

on which the rear end of the pawl *h* may be pivoted. Pawl *h* is arranged at its free end to engage the teeth of ratchet-wheel *i*, forwardly rotated by a crank *j*, secured to the drum-like shaft *k*, upon which the rope *l* is wound, the pawl preventing any slipping or backward movement of said ratchet-wheel, as readily understood. A disk *m* may be arranged on the shaft *k* to assist in guiding the rope as it is wound to place.

o is a tri-iron, being a piece with three arms having holes or other fastening means formed therein. To the end of the rearwardly-extending arm *p* the forward end of the rope may be tied, and to the forward ends of the side arms one of the ends of the links *q* *r* may be secured, the other ends of said links *q* *r* being connected to the lever-arms *s* *t* of the wire-holder *u*, the jaws *v* of which are represented in Fig. 3. The wire passes between the jaws *v* and may be temporarily connected to the rear end of the rope by any suitable means.

In operation all of the functions of the parts are clear to those skilled in the art by an inspection of the drawings. The chain *d* will be passed about a post or pole or other suitable means and fastened, and the crank *j* 75 may be put on the squared end of the shaft *k*, or it may be screwed thereon or fastened in any desirable way, and one end of the rope *l* may be fastened to the shaft *k* in any suitable way, while the other end may be attached to the rearwardly-extending arm *p* of the tri-iron *o*. All of the other parts being arranged as stated, by operating the crank and winding up the rope eventually a pull 80 with any degree of tension may be made on the wire, as will be understood. Splicing 85 may be effected by simply passing the projecting end of the piece to be spliced through the jaws of a separate wire-holder and using another set on the wire-holder, as explained. 90

What is claimed is—

A wire-stretching device comprising a frame including means for its attachment to a post; a shaft journaled in said frame; a drum mounted on said shaft; a rope attached 100 at one end to said drum; a tri-iron secured to the opposite end of said rope; links secured to the forward arms of said tri-iron; a wire-holding member secured at its rear end to the

opposite end of each link, said wire-holding members being pivoted together intermediate their ends and provided at their forward ends with jaws; means for rotating said shaft in one direction, to wind said rope upon the drum thereon and hold the jaws of said wire-holding members in engagement with the wire; and means for preventing re-

verse movement of said shaft and consequent loosening of said jaws from the wire. 10

In testimony whereof I affix my signature in presence of two witnesses.

WALTER P. CHISHOLM.
